CLAIM

The ornamental design for a beverage can cover and seal combination, as shown and described.

DESCRIPTION

FIG. 1 is a top view of a beverage can cover & seal combination showing my new design;

FIG. 2 is an elevated, perspective view of the beverage can cover & seal combination;

FIG. 3 is a bottom view of the beverage can cover & seal combination;

FIG. 4 is an elevated, perspective view, rotated 90°, of the beverage can cover & seal combination;

FIG. 5 is an elevated, perspective view of the underside of the beverage can cover & seal combination;

FIG. 6 is a perspective view in cross-section taken along lines 6—6 of FIG. 3 of the beverage can cover & seal combination; and,

FIG. 7 is a perspective view in cross-section of the beverage can cover & seal combination taken along lines 7—7 of FIG. 3.
